(57) **CLAIM**

The ornamental design for a lip balm caddy, as shown and described.

DESCRIPTION

FIG. 1 is a perspective view of a lip balm caddy showing my new design;

FIG. 2 is a front elevational view, the rear elevational view being a mirror image thereof;

FIG. 3 is a top plan view thereof;

FIG. 4 is a bottom plan view thereof;

FIG. 5 is an end view, the other end view being a mirror image thereof; and,

FIG. 6 is a perspective view of the lip balm caddy with a carabiner-type holder attached to one end.

The broken line showing of a tube of lip balm in FIGS. 1-4 and 6 and the broken line showing of a carabiner-type holder in FIG. 6 is for illustrative purposes only and forms no part of the claimed design.
